UNITED STATES PATENT OFFICE.

STANLEY MOORE, OF MONROE, GEORGIA.

INTERNAL-COMBUSTION ENGINE.

1,280,807.

Specification of Letters Patent.

Patented Oct. 8, 1918.

Application filed July 13, 1917. Serial No. 180,302.

To all whom it may concern:

Be it known that I, STANLEY MOORE, a citizen of the United States, and a resident of Monroe, in the county of Walton and 5 State of Georgia, have invented a certain new and useful Improvement in Internal-Combustion Engines, of which the following is a specification.

My present invention relates generally to 10 internal combustion engines, and more particularly to an engine of this nature of the four-cycle type, my primary object being the provision of an engine in which the fuel oil is supplied to the working cylinder apart 15 from the air necessary for combustion. In my improvement the fuel oil does not enter the working cylinder with the air necessary for its combustion, but is maintained separate therefrom until the time arrives at 20 which the explosion is to take place, and it therefore obviates many of the difficulties experienced in the usual type of engine where the fuel oil enters with the air in gaseous form.

25 Incidentally it is the object of my invention to provide a construction having many advantages over a carbureted fuel supply system, including the elimination of all danger of preignition, the trouble usually encountered in making adjustments of the carburetor, as well as the advantage of a constant pressure supply of oil leading directly to the oil space into which the compressed air is admitted at the time of each explosion. 30 With these and certain other objects in view, together with the advantages to be hereinafter specified, my invention resides in the construction, arrangement, and operation of parts to be now described with reference 35 to the accompanying drawings forming a part of this specification, and wherein—

40 Figure 1 is a side elevation of a two cylinder engine constructed in accordance with my invention, parts of the crank case being broken away;

Fig. 2 is a vertical transverse section taken substantially on line 2—2 of Fig. 1;

Fig. 3 is a detail cross section through the adjustable connecting rod mounting;

45 Fig. 4 is a sectional side view of the part shown in Fig. 3;

Fig. 5 is a detail vertical section taken substantially on line 5—5 of Fig. 2;

Fig. 6 is an enlarged vertical sectional

view through the upper portion of one of the cylinders in the plane of the oil valve;

Fig. 7 is a top plan view of one of the cylinders;

Fig. 8 is a vertical sectional view taken longitudinally through the upper portion 60 of one of the cylinders, substantially on line 8—8 of Fig. 7;

Fig. 9 is a horizontal sectional view showing the arrangement for driving the cam shafts, and

Figs. 10 and 11 are detail perspective views of portions of the said cam shafts.

Referring now to these figures, my improved engine includes cylinders in any desired number, of which each cylinder 15 is disposed vertically and provided in its head with several cavities extending vertically therethrough, of which one receives the cage 16 of the oil intake valve, another receives the cage 17 of the air intake valve, and still another receives the cage 18 of the exhaust valve, the cavities receiving the cages of the air intake and the exhaust valves being in communication with lateral openings of the cylinder head respectively indicated at 19 and 20 and in turn communicating with short pipes 21 and 22.

As seen in Fig. 7 the pipe 21 communicating with the air intake valve is provided with an internal manually adjustable controlling valve 23, preferably of the butterfly type and provided with an externally extending arm 24, and the latter of which is connected at its outer end to an adjusting rod 25 extending along the cylinder and pivotally connected to the lower end of an upright controlling lever 26, the latter of which is fulcrumed upon a bracket 27 extending from the cylinder and as best seen in Fig. 1.

The air intake valve 28, as seen in Figs. 2 and 8, is seated upwardly in the lower inner end of its cage 17, and is provided with a stem projecting vertically through and having bearing in the cage, and an upper external headed end 29 beneath which is a spring 30 normally holding the same in uppermost position with the valve closed, the head 29 being engaged by one end of a controlling lever 31 fulcrumed at 32 upon the cylinder head, and the opposite end of which is pivoted at 33 to the upper end of a cam actuated and vertically disposed rod 34, the lower end of which depends through a bearing in the up-

per portion of the crank case 35 and carries a tappet 36 at its lower end within the crank case.

The valve cage 17 of the air intake valve 5 just described, like the cages 16 and 18 of the oil intake and exhaust valves, has a threaded nut 17^a bearing upon its upper end and for engagement in the upper threaded portion of the cavity of the cylinder 10 in which receives the same, which nut is preferably provided with upper spaced extensions 37 providing for its rotation into and out of engagement with the threaded portion of the cylinder cavity by means of 15 a bar or other straight tool without requiring the use of a wrench. The valve cage may thus be ground to fit and tightly forced and held in place.

The exhaust valve 38 is seated upwardly 20 in the lower end of its cage 18, as best seen in Fig. 8, and has a stem 39 projecting vertically through the cage thereof, with an upper external head 40 normally held in proper position to maintain the valve closed 25 by means of a spring 41 acted upon at proper times by one end of an actuating arm 42 fulcrumed at 43 upon the cylinder head, and the opposite end of which is pivoted at 44 to the upper end of a cam actuated 30 and vertically disposed rod 45, the lower end of which depends into the upper portion of the crank case 35 and carries a tappet 46 at its lower extremity within the crank case, it being noted from Figs. 1 and 7 that the 35 actuating arms 31 and 42 and the cam actuated rods 34 and 45 extend parallel with one another.

The oil intake valve of the cylinder, as seen at 47 in Fig. 6, is seated upwardly in 40 the lower end of its cage 16, and has a piston portion 48 thereabove slidably interfitting the bore of its cage, the lower end of which is reduced as seen at 49 and cooperates with an enlarged internal portion 50 of the 45 cage 60 to form an oil chamber 51 above the valve 47 and normally closed as regards the working cylinder of the engine, by means of said valve. The piston 48 is at the lower end of the valve stem 52, the latter of which extends vertically through the upper end of the cage 16, and has a headed upper end engaged by a spring 53 which normally holds the valve 47 closed. This 50 upper external end of the stem 52 is acted upon by one end of an actuating arm 54 fulcrumed at 55 upon the cylinder head, and the opposite end of which is pivotally connected at 56 to the upper end of a cam actuated rod 57 projecting vertically at the opposite side of the cylinder 15 with respect to the rods 34 and 45. This rod, like the others, extends at its lower end through a bearing in the top of the crank case 35 and is provided at its lower extremity with a 60 tappet 58 within the crank case.

Referring again to Fig. 6, the valve cage 59 is threaded in a horizontal position into one side of the cylinder head, and has its inner end projecting laterally into one side of the cage 16 of the intake valve, and provided with an inner valve seat, outwardly against which is seated an oil feed valve 60, the stem 61 of which projects horizontally through the cage 59, and its external portion is engaged by a spring 62 normally holding the valve 60 seated, and by the inner arm 63 of a bell crank lever fulcrumed at 64 upon one side of the cylinder 15 and the opposite end 65 of which has a yoke partially embracing the cam actuated rod 34 of the air intake valve and acted upon by a collar 66 adjustably secured upon said rod, as seen in Figs. 1 and 2.

The cage 59 of the oil feed valve has an intermediate annular groove 67 in communication with the vertical oil feed channel 68 of the cylinder head, into the upper end of which is threaded one end of an oil feed pipe 69, the latter of which, as seen in Fig. 1, branches from a feed pipe 70 leading from 85 a fuel oil pump 71, the oil fed to the groove 67 flowing through a longitudinal channel 72 of the cage 59, which at one end opens through the seat of the valve 60, and at its opposite end the longitudinal channel 72 90 of the valve cage is controlled by a needle valve 73.

Thus, by means of the pump 71 driven as presently described, a constant pressure is maintained upon the oil supply, so that 100 oil will be forced into the chamber 51 of the oil intake valve, under control of the needle valve 73, each time the feed valve 60 is unseated, so that, with the intake valve 47 in closed position, the chamber 51 will 105 be filled with oil, and upon the compression stroke of the piston 74, previous to which a charge of air has been admitted to the working chamber, this charge of air will be highly compressed, and when the valve 47 is opened as the piston approaches the end of its compression stroke, the air will be forced into the chamber 51 and the high compression will explode the charge without the necessity for sparking or other ignition means.

The cage 16 of the intake valve 47 is provided with a vertical channel 75, as seen in Fig. 6, the lower end of which is in communication with the chamber 51, and the 110 upper external end of which receives the threaded end of a priming valve 76, by means of which oil may be supplied to the chamber 51 at the start of operations.

The piston 74 mounted within the cylinder 15, the latter of which opens at its lower end into the upper portion of the crank case 35, has internal diametrically opposed bosses 77 forming bearings for the reduced end 78 of a wrist pin which, as best seen in Figs. 125 130

3 and 4, has a central enlarged portion 79 provided with a threaded opening for the reception of the upper threaded end 80 of a pitman 81, said upper threaded end having 5 a nut 82 below the wrist pin whereby the extent of upward movement of the piston 74 may be controlled by virtue of the adjustment of the effective length of the pitman 81.

As seen in Fig. 2 in particular the lower 10 end of the pitman connects with the crank 83 of the main shaft 84, the latter of which carries an obliquely toothed gear 85 in mesh with similar toothed gears 86 and 87 mounted upon parallel cam shafts 88 and 15 89 at opposite sides of the vertical plane of the main shaft 84 and partially inclosed by gear casings 90.

The cam shaft 88 supports a cam 91 which acts upon the tappet 58 of the rod 57 of the 20 intake valve 47, which cam is of sufficient size to hold the valve 47 open during the explosion and exhaust strokes of the piston 74.

The opposite cam shaft 89 has cams 92 25 and 93 respectively operating against the tappets 36 and 46 of the rods 34 and 45 of the air intake and the exhaust valves 28 and 38, the rod 34 of which also actuates the oil feed valve 60 through the connections 30 previously described.

The obliquely toothed gear 86 of the cam shaft 88 is, furthermore, splined upon a squared portion 94 of said shaft, as best seen by reference to Fig. 5, and has an annularly 35 grooved extension 95 at one side, engaged by a yoke 96 of an inwardly projecting rod 97, the outer end of which projects externally of the crank case 35 and is connected to the lower end of an upright lever 98 ful- 40 crumed at 99 upon a bracket 100, and having a latch mechanism 101 in engagement with a stationary notched quadrant 102. Thus, by adjusting the gear 86 through the manual manipulation of the lever 98, the parts may 45 be adjusted to vary the time of opening of the intake valve 47 so as to advance or retard the explosions.

The cylinder 15 has a water jacket 103 supplied from a pump 104, the shaft 105 50 of the latter of which is provided with a gear 106 in mesh with the gear 86, parallel with and upon the relatively opposite side of the cylinder 15, as compared to a shaft 107, having a gear in mesh with the gear 87. This shaft 107 extends to and actuates the fuel oil pump 71 before described, and 55 may have means, including a cam 108, as seen in Fig. 2, for actuating and lubricating the oil pump 109, the connections 110 of which, seen broken away in Fig. 1, may lead in any suitable manner desired to the various working parts of the engine requiring lubrication.

The engine described, as first above stated, 60 is a four cycle type in which the explosion

takes place at the end of the compression stroke when the intake valve 47 is open to permit the previously compressed supply of air received through the air intake valve 28 to find its way into the fuel oil chamber 51. At this time the air intake valve 28 is of course closed, and the piston at once moves outwardly in its cylinder under the effect of the explosion, during which time the oil feed valve 60 is closed. As the 70 piston 74 starts inwardly after the power stroke, the exhaust valve 38 opens under actuation of the cam 93, and during this full inward exhausting stroke of the piston 74 the intake valve 47 is open so as to permit the products of combustion to entirely escape from the chamber 51, the exhausting products finding their way outwardly through the lateral cylinder opening 20 to the exhaust pipe 22 before described.

As the piston starts outwardly upon its suction stroke the air intake valve 28 is opened and the fuel intake valve 47 closes, the feed valve 60 opening with the opening of the air intake valve 28, so that, as the piston recedes, sucking in its charge of air, the volume of which may be controlled by the valve 23 before described, oil under the control of the needle valve 73 finds its way into the chamber 51 by virtue of the 90 constant pressure upon the oil supply through the pump 71. At the end of the suction stroke the air intake valve 28 closes and the piston 74 again starts inwardly, this time upon its compression stroke, during 95 which stroke the air supply is thoroughly compressed independent of any fuel, and as the piston arrives at the end of its stroke the fuel intake valve 47 opens and the explosion takes place, as previously described.

It is obvious from the foregoing that my invention provides an arrangement by which the foregoing objects are practically and efficiently carried out and one by which the disadvantages and all operating troubles incident to ignition and combustible charge forming means are entirely eliminated.

I claim:

1. An oil engine having a cylinder provided with mechanically controlled air intake and exhaust valves, and with an oil holding cavity in the head thereof, a valve between the cavity and the working chamber of the cylinder, means for supplying oil to the said cavity, including a mechanically actuated controlling valve, a piston in the cylinder, a power shaft to which the piston is connected, having an obliquely toothed gear, a cam shaft having an obliquely toothed gear in engagement with the said gear of the power shaft, connections for actuating said valve between the oil cavity and the cylinder, and actuated by the cam of said cam shaft, said gear of said cam shaft being splined there- 125

on and shiftable with respect to the gear of the power shaft while in engagement therewith, and manually controlled connections for shifting the said gear whereby to control the time of opening of the valve actuated thereby.

2. An oil engine having a cylinder provided with a plurality of openings in the head thereof, threaded adjacent their outer ends, valve cages interfitting said openings, and in two parts, the outer parts having threaded portions engaging the threads of the openings to firmly seat the inner portions of the cages in position, one of said valve cages having its bore enlarged intermediate its ends to form an oil cavity, in communication with the inner end of another of the cages, an oil intake valve in the first named cage controlling communication between the oil cavity thereof and the working chamber of the cylinder, an oil feed valve between the first and second cages controlling the feed of oil to the said oil cavity, air intake and exhaust valves in certain other of the cages in communication

with the working chamber of the cylinder, a piston operating in the cylinder, and mechanical connections between the piston and the several valves for actuating the latter.

3. An oil engine having a cylinder provided with air intake and exhaust valves and an oil cavity, an oil intake valve between the said oil cavity and the working chamber of the cylinder, means for feeding oil to the cavity, including a controlling valve adjacent the cavity, a piston operating in the cylinder, mechanical connections between the piston and the said oil feed valve and the air intake and exhaust valves for actuating the latter, including a cam actuated rod having an air intake valve, a collar adjustably disposed thereon, and a lever engaging the oil feed valve and having a portion thereof disposed in the path of movement of the said collar.

STANLEY MOORE.
